COLLAR STRAIGHTENING STRIP

Rodolfo Tos, New York, N. Y.

Application September 9, 1938, Serial No. 229,083

2 Claims. (Cl. 2—132)

This invention relates to new and useful improvements in a collar straightening strip.

The invention has for an object the construction of an article as mentioned which is adapted 5 to be conveniently secured to the rear face of a point portion of a soft collar for holding the point portion straight.

More specifically, the invention contemplates characterizing the article by a flat body adapted 10 to be placed against the rear face of a point portion of a soft collar, and pins attached upon the front face of the body in a particular manner to efficiently and conveniently support the flat body in position.

15 More particularly, the invention contemplates extending the pins along portions of the front face of the flat body in a manner so that they have their points slightly spaced from the face of the flat body and that the points are directed 20 away from each other. When thus constructed it is possible to first engage one pin into a portion of the material of the soft collar, and to engage the other pin in a manner so that the flat body is held in position.

25 Still further the invention proposes to provide the collar straightening strips in pairs, one a right hand article for engaging one of the points of a collar, and the other a left hand article for engaging the other point of the collar.

30 Still further the invention contemplates the use of reinforcement elements extending along the flat body for reinforcing and stiffening the same.

35 Another object of the invention resides in an arrangement for releasably holding each of the pins so that they may be removed and replaced when desired, and furthermore be movable from the front face of the flat body to the rear face to convert the article from a right hand article 40 to a left hand article, and vice versa.

For further comprehension of the invention, and of the objects and advantages thereof, reference will be had to the following description and accompanying drawing, and to the appended claims in which the various novel features 45 of the invention are more particularly set forth.

In the accompanying drawing forming a material part of this disclosure:

50 Fig. 1 is a perspective view of a soft collar equipped with collar straightening strips constructed according to this invention.

Fig. 2 is a vertical sectional view taken on the line 2—2 of Fig. 1.

55 Fig. 3 is a perspective view of a "left" collar

straightening strip constructed according to this invention.

Fig. 4 is a perspective view of a "right" collar straightening strip constructed according to this invention. 5

Fig. 5 is a fragmentary enlarged vertical sectional view on the line 5—5 of Fig. 4.

Fig. 6 is an elevational view of one of the pins used in the device.

Fig. 7 is a horizontal sectional view on the line 10 7—7 of Fig. 4.

Fig. 8 is a fragmentary perspective view of a collar straightening strip constructed according to a modification of this invention.

Fig. 9 is an enlarged elevational view of a portion of Fig. 8. 15

Fig. 10 is a horizontal sectional view on the line 10—10 of Fig. 9.

In Fig. 1 a soft collar 10 is illustrated having a left point 10^a and a right point 10^b. Collar 20 straightening strips, according to this invention, are secured to the rear faces of each of the point portions 10^a and 10^b as indicated in Fig. 1. The collar 10 is of standard construction and has a front portion 10^c and a band portion 10^d. 25 It is on the rear face of the front portion 10^c that the collar straightening strips are secured.

Each of the collar straightening strips is substantially of identical construction except for the fact that one is "right" and one is "left". The 30 "left" strip (see Fig. 3) comprises a flat body 11 adapted to be placed against the rear face of the point portion 10^a of the soft collar 10. Fins 12 are attached upon the front face of the body 11 and extend along the face and have their 35 points slightly spaced from the face of the flat body 10, as clearly shown in Fig. 5. The space referred to is indicated in this figure by numeral 13. The points of the pins 12 are directed away from each other so that the flat body may first 40 be moved in one direction to engage one pin into the material of the collar, and slightly moved in the other direction to engage the other pin in a manner so that both pins are engaged. The flat body 11 is of V-shape in elevation. It is 45 formed with one of the arms 11^a slightly shorter than the arm 11^b. The long arm 11^b is reinforced by a stiffening rib 14 embossed into the material thereof. This rib is pressed into the front face of the flat body 10 and projects out from the rear 50 face (see Fig. 7).

Because of the different lengths of the arms of the V-shaped body it is possible to use the collar straightening strip with collars having somewhat different lengths of pointed portions. 55

When the collar has shorter points the short arm of the V-shaped body is used along the points. For a longer point the long arm 11^b is used along the point. Of course, when there is a change 5 from the long to the short arm it is necessary to turn around the flat body, and then the device which heretofore was considered a "left" device now must be used on the right point of the collar. In the same way the "right" device may be turned 10 around and used in the left point of the collar.

In Fig. 4 a "right" device is illustrated. This device has a flat body 11 of V-shape with the arm 11^a thereof towards the right, and the long arm 11^b thereof towards the left which is distinctly 15 opposite to the location of the arms in the "left" device illustrated in Fig. 3. The long arm 11^b is formed with a reinforcement rib 14. Pins 12 are attached on the front face of the body 11. These pins are arranged spaced from each other 20 with their points directed away from each other.

Each of the pins 12 is attached to the front face of the flat body in the following manner: Each pin 12 is formed at its base with an annular portion 12^a. An eyelet 16 is engaged through the 25 annular portion 12^a and through an opening 17 formed in the material of the flat body. The eyelet 16 has its flanges tightly pressed downwards firmly to hold the pin as required. This prevents the pin from turning. Because of the 30 tapering of the pin from its base to its point there will be the space 13 previously referred to.

The collar straightening strip is attached to the point of the collar by merely placing the flat body of the strip flat against the rear face of the 35 collar and then moving the collar straightening strip first in one direction to engage one of the pins 12 into the material of the collar, and then slightly back in the other direction to engage the second pin. The engagement of both pins serves 40 to hold the straightening strip in position. The straightening strip will serve to prevent the points of the collar from turnings up and give an untidy appearance.

In Figs. 8-10 inclusive a modification of the 45 invention has been disclosed which distinguishes from the prior form in several respects. According to this form there is an opening 17^a formed beneath each of the pins 12. It is possible to press a small area of the material of the soft 50 collar into the opening, from the outer face of the collar, to facilitate the easy engagement of the pin 12 into this material. Each of the openings 17^a is of bayonet form, that is, at one end there is a large portion 17^{aa} and at the other end 55 a reduced portion 17^{bb}. In this reduced portion the eyelet 16 engages. This eyelet 16 holds the pin 12 in a manner similar to that previously described.

The distinction lies in the fact that normally the eyelet is disposed in the small end 17^{bb} of the bayonet opening. It may be forced into the large end 17^{aa} and then removed completely from the opening. The advantage of this construction resides in the fact that the pins may be changed and substituted whenever required, and moreover, may be placed into the opening to be disposed upon the front face or the back face of the flat body. A change of this character will change 10 the collar straightening strip from a "right" to a "left", or vice versa.

While I have illustrated and described the preferred embodiments of my invention, it is to be understood that I do not limit myself to the 15 precise constructions herein disclosed and the right is reserved to all changes and modifications coming within the scope of the invention as defined in the appended claims.

Having thus described my invention, what I 20 claim as new, and desire to secure by United States Letter Patent is:

1. A collar straightening strip, comprising a flat body adapted to be placed against the rear face of the pointed portion of a collar, said flat body being formed with a bayonet slot at each end thereof, said bayonet slots having their enlarged ends directed away from each other, eyelets adapted to be passed through the enlarged ends of said slots and into the small end of said 30 bayonet slots, and pins engageable into said collar and mounted on one end of said eyelets and having their points directed away from each other and superimposed upon the enlarged portion of said bayonet slots permitting a portion of said 35 collar to be urged into the enlarged end of said bayonet slots to facilitate its engagements upon said pins.

2. A collar straightening strip, comprising a flat body adapted to be placed against the rear face 40 of the pointed portion of a collar, said flat body being formed with a bayonet slot at each end thereof, said bayonet slots having their enlarged ends directed away from each other, eyelets adapted to be passed through the enlarged ends 45 of said slots and into the small end of said bayonet slots, and pins engageable into said collar and mounted on one end of said eyelets and having their points directed away from each other and superimposed upon the enlarged portion of said bayonet slots permitting a portion of said 50 collar to be urged into the enlarged end of said bayonet slots to facilitate its engagements upon said pins, said eyelets being removable from said bayonet slots to permit them to be 55 engaged therewith with said pins laying adjacent either face of said flat body.

RODOLFO TOS.
